CLAIM

The ornamental design for a slide for transferring invalid between wheel chair and auto seat, as shown.

DESCRIPTION

FIG. 1 is a perspective view of a slide for transferring invalid between wheel chair and auto seat showing my new design;

FIG. 2 is a top plan view thereof;

FIG. 3 is a front elevation view thereof;

FIG. 4 is a first end elevation view thereof;

FIG. 5 is a rear elevation view thereof;

FIG. 6 is a second end elevation view thereof; and

FIG. 7 is a bottom plan view thereof.
